UNITED STATES PATENT OFFICE.

RAYMOND A. WAITE AND GEORGE W. LAUTRUP, OF YONKERS, NEW YORK, ASSIGNEES TO OTIS ELEVATOR COMPANY, OF JERSEY CITY, NEW JERSEY, A CORPORATION OF NEW JERSEY.

ELECTRIC ELEVATOR SYSTEM.

Application filed June 18, 1924. Serial No. 720,763.

This invention relates to an improved control system for electric elevators and more particularly to the operation of the elevator car in starting, passing from one speed to another, stopping, reversing, and leveling at the various landings.

The system according to the present invention includes a hoisting motor, a motor generator set adapted to supply power to 10 said hoisting motor at a variable voltage for operating it in either direction at various speeds, a brake adapted to have a slow, medium and quick operation in its application, a governor operative for regulating 15 fields of the hoisting motor and generator in the event of the motor operating above a predetermined speed, and various devices used in connection with the operation of the hoisting mechanism to insure that the elevator car is brought level with the landings 20 accurately and smoothly.

The control system is provided with a car switch in the elevator car for operating the car at normal speeds in either direction and 25 for stopping the car. Leveling switches carried by the elevator car and adapted to be actuated by cams in the elevator hatchway operate the elevator car for bringing the car level with the landings. The brake has 30 electromagnetic releasing means having connections with the control system for a quick application of the brake when the elevator car has been brought to the landing by the leveling switches, for a medium application 35 thereof during a reversal of the car by the car switch, and a slow application of the brake during the stopping of the elevator car outside of the leveling zones. The control system also provides a means for mo- 40 mentially increasing the current in the generator field winding when the elevator car is being leveled whereby the car is brought quickly and positively to the landing level. The generator has a series field winding and 45 means are provided for varying the ampere turns of the series field for a given current through the armature,—as for example by varying the resistance of a shunt around the series field so that the effect of the series 50 field is different during operation by the car switch from that during operation on the leveling switch. The brake is provided with a switch for rendering the control system inoperative to accelerate the car above

a certain speed until after the brake has been 55 released. The leveling switches in cooperation with cams in the hatchway at the various landings are arranged to operate the control system, and are rendered operative for such purpose during the retardation of 60 the car before it has come to rest, so that the elevator car is brought smoothly to the landing level. Means are provided in the control system whereby it is possible to bring the car under the control of the car switch 65 at any time during the operation of the car by the leveling switches, and operate it in either direction by the car switch. Certain switches are provided with parallel resistances, or inductances or both in the circuits 70 of their coils for retarding their operation so as to obtain a smooth operation of the elevator car in accelerating, retarding, stopping and reversing.

This invention will be described in connection with the accompanying drawings, wherein one embodiment of the invention is illustrated and in which:

Figure 1 is a diagrammatic view of an elevator system; and

Figure 2 is a simplified (straight) wiring diagram, of the system illustrated in Figure 1, wherein the coils and contacts of the various switches are shown as separate elements and wherein the letters indicating the various switches to which the respective coils and contacts belong are prefixed to the reference numerals.

The switch contacts shown sectioned represent the stationary contact elements of the 90 various switches.

Referring to the drawings, the driving motor E with its shunt field EF receives power from the line through knife switch I. This motor drives generator GE, and these 95 two units comprise a motor generator set. The generator GE supplies power of a variable voltage to hoisting motor M. This variable voltage is obtained by control of the separately excited generator field GF. The elevator car K and the counterweight CWT are operatively connected to the driving motor M by cable 1. The operating switch A is located in the car K and serves to control the running of the elevator. A leveling 100 switch L is located on top of the car and in conjunction with cams 2 and 3 located in the hatchway serves to control the leveling 105

of the car with the floor landings. The control system includes reversing, accelerating and relay switches for controlling the operation of the elevator by the operating switch A; also other relay switches for controlling the leveling of the elevator car with the various landings. Power for the control circuits is supplied through knife switch J. The switches are all shown in their de-
10 energized position, the car being located level with the second floor landing.

Assume that it is desired to run the elevator from the position shown in an upward direction and then stop it at the third floor landing. The operator in the car moves the lever 4 of the operating switch A to the left for an up motion of the elevator. The contact segment 5 of the operating switch A bridges switch fingers 6, 7, 8, 9, 10 and 11.

20 When contact segment 5 bridges fingers 6 and 7 a circuit is completed for the actuating coils of the up reversing switch B and the auxiliary field switch H as follows—from the minus supply line, through knife switch J, by wire 12, by wire 13, by wire 14, through back contact 15 of down reversing switch C, by wire 16, by wire 17, finger 6, segment 5, finger 7, by wire 18, through actuating coil 19 of up reversing switch B, by wire 20, through actuating coil 21 of auxiliary field switch H, by wire 22, by wire 23, by wire 24, through knife switch J to the plus supply main.

The energization of coil 21 of switch H causes this switch to operate and close its upper contacts and open its lower contact. The closing of contact 25 of switch H closes the common feed from the plus supply line to the coils of the accelerating switches D, E, F, and G as will be described below in connection with the circuits for these coils. The closing of contact 26 of switch H short circuits the economizing resistance SR, in series with the field MF of the hoisting motor M the circuit being as follows—from the minus supply line, through switch J, by wire 12, by wire 13, by wire 27, through back contact 28 of switch G, by wire 29, by wire 30, through contact 26 of switch H, by wire 31, by wire 32, through field MF and resistance PFR in parallel, by wire 33, through switch J to the plus supply line. The closing of this circuit puts full field on the hoisting motor M. The closing of contact 34 of switch H makes circuit for the magnet of the brake BR as follows: from the minus supply line, through switch J, by wire 12, by wire 35, through contact 34 of switch H, by wire 36, through switch contact 37 on the brake BR, by wire 38, by wire 39, through coil 40 of brake BR, by wire 41, by wire 24, through switch J to the plus supply line. This results in the release of the brake from the hoisting motor M and opening of the switch contact 37 on brake BR.

The opening of switch contact 37 on brake BR inserts in series with brake coil 40 a resistance ABR, and the coil of an auxiliary accelerating switch O and its series resistance OR in parallel with resistance ABR. The circuit is: from the minus line to wire 36 as previously traced, through resistance ABR and by wire 42 in parallel with the circuit through resistance OR, by wire 43, through coil 44 of switch O; and thence by wire 39, through coil 40 of brake BR, by wire 41, by wire 24, through switch J to the plus supply line. The energization of coil 44 of switch O causes this switch to operate and close its contact 45 for timing the accelerating switches E, F, and G, the circuits for which will be hereinafter set forth. The purpose of this arrangement is to utilize the time constant of the brake for timing the accelerating switches, and also for saving power by preventing the acceleration of the car above low speed until the brake has been released. The brake magnet is energized at the same time that power is put on the motor, but the shoe does not lift at once because the magnet itself has an inherent time constant and, also because the shoes (and lever arms, not shown in the diagrammatic representation) represent considerable mass which must be set in motion. When contact 37 on the brake opens, inserting resistance ABR in series with the magnet coil 40, the current is cut down and hence, the heating of the magnet coil. The switch O in parallel with resistance ABR will operate as the 100 brake shoe lifts, and close its contact 45 for the accelerating switches E, F and G.

The opening of contact 46 of switch H opens the circuit of resistance PBR¹, which is in parallel with the coil of the brake. There are two other resistances, PBR and PBR², in parallel with the brake coil, the circuit through these resistances being completed simultaneously with the energization of the brake coil. The circuit of these parallel resistances when the lower contact 46 of switch H and contacts of switch Y are closed is as follows: from the coil 40 of brake BR, by wire 39, by wire 38, through contact 37 of brake BR, by wire 36, by wire 47, by parallel circuits through resistances PBR, PBR¹ and PBR²; the parallel circuit for PBR being from wire 47, through PBR, by wire 52, by wire 23, to wire 24; the parallel circuit for resistance PBR¹ being by wire 48, through contact 49 of switch Y, by wire 50, through resistance PBR¹, by wire 53; through contact 46 of switch H, by wire 23 to wire 24; the parallel circuit for PBR² being by wire 48, through contact 49 of switch Y, by wires 50 and 51, through resistance PBR², by wire 52, by wire 23, to wire 24; the combined circuit from wire 24 extends by wire 41 to coil 40 of brake BR. The purpose of these resistances is to control 125

the application of the brake under different conditions of operation as will hereinafter be described.

The energization of the coil 19 of the up reversing switch B as described above causes this switch to operate and close its upper contacts and open its lower contacts. The switches B and C are interlocked by means of a walking beam 54 pivotally mounted for 10 engaging catches on the cores 55 and 56 of the switches B and C so that when one is operated the other is prevented from operating while the first one is energized. The closing of the contacts 57 and 58 of switch B completes the circuit for the field GF of generator GE as follows; from the minus supply line, through switch J, by wire 12, by wire 59, by wire 60, through contact 57 of switch B, by wire 61, by wire 62, through 15 field GF, by wire 63, through coil 64 of relay N, by wire 65, through coil 66 of relay Q, by wire 67, by wire 68, through contact 58 of switch B, by wire 69, through a part of resistance GFR to the point 79, by wire 70, 20 through back contact 71 of relay R, by wire 72, by wire 24, through switch J to the plus supply line. While the circuit for the coils of relays N and Q is now complete, these relays do not operate as the current is too low 25 due to the resistance GFR in series with these coils and the field GF. The closing of this circuit however energizes the field GF and the generator GE will generate sufficient voltage to cause the motor M to start, 30 the armature of the latter being connected across the armature of the generator. The contact 73 of switch B closes coincident with the closing of contacts 57 and 58, but does not complete any circuit at this time. The 35 opening of contacts 74 and 75 of switch B opens the circuits to the down direction feed to the car switch A and the feed from the down side of the car switch to the accelerating switches respectively.

40 When the segment 5 of the operating switch bridges fingers 6 and 8, a circuit is completed for the actuating coil 77 of leveling switch relay T as follows; from the minus line to finger 6 as previously traced, segment 5, finger 8, by wire 76, through actuating coil 77 of switch T, by wire 78, by wire 52, by wire 23, by wire 24, through switch J to the plus supply line. The switch T closes its contact, completing the circuit 45 for the leveling switch motor LM as follows; from the minus supply line, through switch J, by wire 12, by wire 80, through contact 81 of switch T, by wire 82, through leveling switch motor LM, by wire 83, by wire 24, through switch J, to the plus supply line. The energization of the leveling switch motor results in the switch arm 86 with its roller 87 being moved away from the cam 2 and the switch arm 88 with its roller 89 be-

ing moved away from cam 3, these two arms 65 being connected to the motor LM by arm 85 and connection 84. The leveling switch arms are then in such a position that their rollers will not strike the cams 2 and 3 as the car moves and the leveling switch contacts are 70 kept open.

With switches B, H, and T energized as just outlined, the motor M will run at a speed corresponding to the voltage supplied by the generator GE. The voltage of this 75 generator is increased in successive steps by short circuiting portions of the resistance GFR in series with the field GF. When segment 5 bridges fingers 6 and 9, a circuit is completed for coil 94 of the first accelerating switch D as follows; from the minus supply line to finger 6 as previously traced, segment 5, finger 9, by wire 90, through back contact 91 of down reversing switch C, by wire 92, through series resistance AR², 80 by wire 93, through coil 94 of accelerating switch D, by wire 95, through contact 96 on switch E, by wire 97, through contact 98 on switch Q, by wire 99, through contact 25 of switch H, by wire 22, by wire 23, by wire 24, 90 through switch J to the plus supply line. Switch D is thereby energized and closes its top contacts and opens its bottom contact.

The closing of contact 108 of switch D completes the circuit for the holding coils of 95 switches B, H and T as follows; from the minus supply line, through switch J, by wire 12, by wire 100, through holding coil 101 of switch T, by wire 102, by wire 103, through contact 73 on switch B, by wire 104, through holding coil 105 of switch B, by wire 106, by wire 107, through contact 108 of switch D, by wire 109, by wire 110, through holding coil 111 of switch H, by wire 22, by wire 23, by wire 24, through switch J to the plus supply line. This circuit for the coils of 100 switches B, H, and T is independent of the circuits originally completed for the actuating coils of these switches. The opening of back contact 112 of switch D removes the short circuit around coil 101 of switch T, this contact being connected to the two ends 105 of this coil by wires 113 and 114.

The closing of contact 118 of switch D short circuits a portion of resistance GFR as 115 follows; from point 115 in resistance GFR, by wire 116, by wire 117, through contact 118 of switch D, by wire 119, to point 205. Resistance XFR has a short circuit as follows; from point 205, by wires 119, 120 and 121, through contact 122 of switch V, by wire 123, by wire 24, by wire 203, to point 204. By thus short circuiting a portion of the resistance GFR, the voltage supplied by the generator GE is increased and the hoisting motor M will run at an increased speed. The closing of contact 127 of switch D completes the circuit for the second and third 120 125

accelerating switches when car switch A bridges the fingers 6 and 10 as will be described below.

When segment 5 of operating switch A bridges fingers 6 and 10, a circuit is completed for coil 130 of the second accelerating switch E as follows; from the minus supply line to finger 6 as previously traced, segment 5, finger 10, by wire 124, through resistance AR³, by wire 125, through contact 45 of auxiliary accelerating switch O, by wire 126, through contact 127 of switch D, by wire 128, by wire 129, through coil 130 of switch E, by wire 95, through contact 96 of switch E, by wire 97, through contact 98 of switch Q, by wire 99, through contact 25 of switch H, by wire 22, by wire 23, by wire 24, through switch J to the plus supply line. Resistances ARP² and ARP³ are in parallel with the coils of switches D and E respectively; the circuit for resistance ARP² being from coil 94 of switch D, by wire 95, contact 96 of switch E, by wire 97, contact 98 of switch Q, by wire 99, through resistance ARP², by wires 131 and 93 back to coil 94; and the circuit through ARP³ being, from coil 130 of switch E, by wire 95, contact 96 of switch E, by wire 97, contact 98 of switch Q, by wire 99, through resistance ARP³, by wires 128 and 129 back to coil 130. These resistances have no function during the closing of switches D and E but act when the switches are deenergized. Switch E is energized through the circuit above traced and opens its bottom contact 96. The opening of bottom contact 96 opens the short circuit extending from inductance 140, by wire 95, through contact 96 of switch E, by wire 97, through contact 98 of switch Q, by wires 99 and 141, back to inductance 140, so that inductance 140 is inserted in the circuit of coil 130 of switch E. The insertion of inductance 140 in the circuit of coil 130 of switch E delays its action in closing its top contacts. The closing of contact 134 of switch E short circuits another portion of the resistance GFR as follows; from point 132 in resistance GFR, by wire 133, through contact 134 of switch E, by wire 117, through contact 118 of switch D, by wire 119, to point 205 of resistance GFR. By thus short circuiting another portion of the resistance GFR, the voltage supplied by the generator GE is further increased and the hoisting motor M runs at an increased speed. The closing of contact 135 of switch E completes the circuit for coil 139 of the third accelerating switch F as follows: from the minus supply line to finger 10 as previously traced, by wire 124, through resistance AR⁴, by wire 136 through contact 135 of switch E, by wire 137, by wire 138, through coil 139 of switch F, by wire 95, through inductance 140, by wires 141 and 99, through contact 25 of switch H, by wires 22, 23 and 24, through switch J to

the plus line. Resistance ARP⁴ is connected in parallel with coil 139 of switch F and inductance 140, by wires 138 and 137, through resistance ARP⁴ and by wires 99 and 141, through inductance 140, by wire 95 back to coil 139. Switch F will then operate, its action being delayed by the inductance 140 in series with its coil. The closing of contact 144 of switch F short circuits another portion of resistance GFR as follows; from point 142, by wire 143 through contact 144 of switch F, by wire 133, through contact 134 of switch E and contact 118 of switch D to point 205. By thus short circuiting another portion of the resistance GFR, the voltage supplied by the generator GE is further increased and the speed of the hoisting motor M is increased.

By the time switches E and F have closed, the current in the generator field GF has increased sufficiently to cause the switches Q and M, the coils of which are in series with the generator field, to operate. The contact 145 of switch N is in parallel with contact 108 of switch D and when closed establishes a holding circuit for the coils of switches B, H and T, that is independent of switch D.

When segment 5 of operating switch A bridges fingers 6 and 11, a circuit is completed for the coil 150 of the fourth accelerating switch G as follows; from the minus supply line to finger 6 as previously traced, segment 5, finger 11, by wire 146, through resistance AR⁵, by wire 147, through contact 148 of switch F, by wire 149, through coil 150 of switch G, by wire 95, through inductance 140, by wire 141, by wire 99, through contact 25 of switch H, by wire 22, by wire 23, by wire 24, through switch J to the plus supply line. Switch G closes its upper contacts and opens its lower contact as a result of the completion of this circuit, its action being delayed by the inductance 140 in series with its coil. The closing of contact 153 of switch G short circuits another portion of the resistance GFR as follows; from the point 151 in resistance GFR, by wire 152, through contact 153 of switch G, by wire 143, through contact 144 of switch F, by wire 133, through contact 134 of switch E, by wire 117, contact 118 of switch D, by wire 119, to point 205. By thus short circuiting another portion of the resistance GFR, the voltage supplied by the generator GE is further increased and the speed of the hoisting motor M is again increased. The opening of lower contact 28 of switch G opens the short circuit by wires 27, 13 and 29 around resistance SFR to insert it in series with the field MF of hoisting motor M, thereby weakening this field and causing the motor to run faster. Previous to the opening of contact 28 of switch G, the coil 154 of switch Z was short circuited by

- this contact and contact 26 of switch H in series as follows; from coil 154 of switch Z, by wires 155, 32 and 31, through contact 26 of switch H, by wires 30 and 29, through contact 28 of switch G, by wires 27 and 13, and through resistance ZR back to coil 154. When contact 28 opens, the resistance SFR is placed in parallel with the coil of switch Z. By properly proportioning resistance SFR and resistance ZR in series with the coil, the coil of switch Z will be sufficiently energized at this time to cause this switch to operate. The circuit for the coil of switch Z is as follows; from the minus supply line through switch J, by wire 12, by wire 13, through series resistance ZR, through coil 154 of switch Z, by wire 155, by wire 32, through the field MF, by wire 33, to the plus supply line, and resistance SFR is connected across coil 154 of switch Z and resistance ZR, one end of resistance SFR being connected with resistance ZR and the other by wires 29 and 30, through contact 26 of switch H, by wires 31, 32 and 155. Contact 158 of switch Z together with the contact 160 of switch G short circuits the last portion of resistance GFR as follows; from point 156 on resistance GFR, by wire 69, by wire 157, through contact 158 of switch Z, by wire 159, through contact 160 of switch G, by wire 152, through contact 153 of switch G, by wire 143, through contact 144 of switch F, contact 134 of switch E, and contact 118 of switch D to point 205. By thus short circuiting all of the resistance GFR, the generator supplies full voltage to the hoisting motor M and the latter runs at full speed, hoisting the elevator car at its full speed.
- It is to be noted that the opening of the short circuit around inductance 140, as described in connection with the operation of switch E, connects one end of this inductance to one end of each of the coils of switches D, E and F, while the other end of inductance 140 is connected through resistances ARP², ARP³ and ARP⁴ with the other ends of the coils of switches D, E and F respectively. The object of this inductance is for timing the closing of switches E and F and in conjunction with parallel resistances, the opening of switches D, E and F. It is to be further noted that inductance 140 is in the circuit of the coil of switch G, the purpose being for timing its closing but it has no effect in timing its opening.
- In the event that the elevator car should exceed the rated speed, after the resistance GFR has been entirely short circuited and the resistance SFR inserted in series with the motor field MF, a governor GOV operates to short circuit the resistance SFR and at the same time to deenergize switch Z. Governor GOV is shown driven from the shaft of motor M, and is provided with a contact 161 which is normally open. When the rated speed of the elevator car is exceeded, the governor closes this contact and coil 154 of switch Z and its series resistance ZR, and resistance SFR in parallel therewith are short circuited as follows: from resistance SFR, and resistance ZR, by wire 13, by wire 12, through contact 161 of the governor switch, by wire 162, by wire 32, by wire 155 to the other side of coil 154 of switch Z, which is connected by wires 32 and 31 through contact 26 of switch H, by wire 30, by wire 29, to the other side of resistance SFR. The resistance SFR is thus cut out of the circuit of the motor field MF, and the deenergization of switch Z reinserts the last portion of resistance GFR in the circuit of the generator field GF so that the speed of the motor is decreased by the combined effect of change of field strength of both the hoisting motor and generator.
- Thus at full speed of the elevator the switches B, D, E, F, G, H, N, O, Q, T and Z are energized, the switches C, P, R, V, X and Y being deenergized, all of the latter switches except C, which is the down reversing switch, being used only during the leveling operation.
- When the car approaches the third floor landing, the operator centers the car switch A, thereby disconnecting the fingers 7, 8, 9, 10 and 11 from the feed finger 6. The last accelerating switch, G, will open immediately, there being no resistance in parallel with the coil of this switch to delay its opening. The opening of the upper contacts of this switch inserts part of the resistance GFR in series with the field GF of generator GE, thereby causing the voltage of the generator to be lowered and the speed of the hoisting motor M to be correspondingly reduced. The closing of the lower contact of switch G short circuits the resistance SFR and the coil 154 of switch Z, causing the latter to open its contact. The strength of field MF is thereby increased resulting in a reduction in speed of hoisting motor M. The accelerating switches D, E and F then open, the opening of these switches being delayed by the effect of the inductance 140 in series with their coils and the resistances ARP², ARP³ and ARP⁴ in parallel with the inductance and the coils. By properly proportioning these resistances and the inductance, the desired delayed opening of these switches can be obtained. The opening of these accelerating switches inserts the resistance GFR in successive steps in series with the generator field GF, causing the voltage of this generator to be reduced and thereby gradually reduce the speed of the hoisting motor M.
- As each step of the resistance GFR is inserted in series with the field GF, the strength of the latter is reduced. A sudden

change is prevented, as each step of resistance is inserted, by the action of the resistance GPR in parallel with the field GF and coils of switches N and Q. The circuit for this resistance is as follows; from one end of field GF, by wire 62, through resistance GPR, by wire 68, by wire 67, through coil 66 of switch Q, by wire 65, through coil 64 of switch N, by wire 63 to the other end 10 of field GF. This arrangement also delays the opening of switches N and Q, the contact of switch Q remaining open to keep inductance 140 in the circuit with the accelerating switches for timing their operation in opening, and the contact of switch 15 N maintaining the circuit of the holding coils of switches B, H and T.

When switch D opens, its back contact 112 closes and short circuits the holding coil 101 20 of switch T. This causes switch T to open and disconnect the leveling switch motor LM from the line. The arm 85 of the leveling switch L will move downward, tending to move the arms 86 and 88 toward the cams 25 2 and 3 respectively. Assume that the operator in the car centered the car switch when the car was at a distance from the third floor landing such that, at the time the leveling switch arms drop back, the roller 87 on 30 arm 86 strikes against the high surface 163 of cam 2. This results in the closing of the upper contacts of the leveling switch, thereby completing the circuits for the leveling operation.

35 The leveling switch has two movable arms 86 and 88, pivoted on an arm 164. Arm 164 is connected with arm 85 and is pivotally mounted. Arms 86 and 88 can move independently of arm 85, but an upward movement of arm 85 results in the movement of arms 86 and 88 away from the cams 2 and 3 respectively. Arms 86 and 88 of the leveling switch each have two sets of contacts, those on arm 86 controlling the up motion of 40 the car and those on 88 controlling the down motion, one contact of each set being for fast speed and one for slow speed.

When the leveling switch motor LM is de-energized and the roller 87 on arm 86 bears 50 against the surface 163 of cam 2, the up set of contacts of the leveling switch is closed. The closing of contact 169 completes the circuit for the actuating coils of the up reversing switch B and of the switch H as follows; 55 from the minus supply line, through switch J by wire 12, by wire 165, through coil 166 of switch P, by wire 167, by wire 168, through contact 169 of leveling switch, by wire 18, through coil 19 of switch B, by wire 20, 60 through actuating coil 21 of switch H, by wires 22, 23 and 24, through switch J to the plus supply line. If the reversing switch B is still energized at this time as a result of switch N not having opened its contact 145,

which is in the circuit of the holding coil 105 65 of switch B, the closing of contact 169 of leveling switch L, will merely establish a circuit to permit coil 19 of switch B to maintain switch B closed. If however, switch B should have opened at this time, the energization of coil 19 of this switch by the closing of contact 169 of the leveling switch, results in the closing of switch B again and the re-establishment of the circuits to the generator field GF. The closing of the other 70 contact, 171, of the leveling switch establishes another short circuit around the resistance XFR, this resistance being already short circuited by the contact 122 of switch V as follows; from point 204, by wires 203, 80 24 and 123, through contact 122 of switch V, by wires 121, 120 and 119, to point 205. The short circuit established by the leveling switch is as follows; from point 205, by wire 119, by wire 120, by wire 170, through contact 171 of leveling switch L, by wire 172, by wire 83, by wires 24 and 203 to point 204.

When contact 169 of the leveling switch closes, the coil 166 of switch P is energized 90 and this switch closes its contact, completing the circuit for the coil of switch R as follows; from the minus supply line, through switch J, by wire 12, through coil 173 of switch R, by wire 174, through contact 175 95 of switch P, by wire 176, by wire 52, by wire 23, by wire 24, through switch J to the plus line. Switch R closes its three upper contacts and opens its lower contact.

The opening of lower contact 71 of switch 100 R removes the short circuit from the portion of resistance GFR, between points 79 and 205, thereby inserting all of resistance GFR in the field. The circuit through the resistance GFR is then as follows; from the minus 105 line to point 79 of resistance GFR as previously traced in connection with the operation of switch B, through all of resistance GFR, to point 205, by wire 119, by wires 120 and 121, through contact 122 of switch V, 110 by wires 123 and 24 to the plus line. As above stated, contact 171 of the leveling switch is in parallel with contact 122 of switch V. The elevator is then running at a speed slightly lower than the lowest speed 115 obtainable by the car switch.

One of the upper contacts of switch R connects the up and down feed fingers 6 and 180, of the car switch A as follows; from finger 6, by wire 17, by wire 16, through contact 177 of switch R, by wire 178, by wire 179, to finger 180. The object of this contact is to permit the operator in the car to take the control away from the leveling switch and to operate the car in either direction by the car switch at any time during the leveling operation as will hereinafter be set forth. Without this connection, it would be possible

for the operator to take the control during the leveling operation only in the direction in which the car is moving.

Upper contact 185 of switch R completes the circuit for the coil of switch V as follows; from the minus supply line, through switch J, by wire 12, through coil 181 of switch V, by wire 182, through inductance 183, by wire 184, through contact 185 of switch R, by wire 186, by wire 52, by wire 23, by wire 24, through switch J to the plus supply line. Switch V opens its contact 122, but the opening of this contact has no effect at this time, as contact 171 of leveling switch 10 is closed and in a circuit parallel to contact 122 of switch V. The operation of switch V in opening its contact 122 is retarded by the action of the inductance 183 in series with its coil.

20 The third upper contact, 190, of switch R completes the circuit for the coil of switch X as follows; from the minus supply line, through switch J, by wire 12, through coil 187 of switch X, through inductance 188, by wire 189, through contact 190 of switch R, by wire 191, by wire 52, by wire 23, by wire 24, through switch J to the plus line. A resistance PR² is placed in parallel with the coil of switch X and the inductance 188 to 25 regulate the opening of this switch. When the coil 187 of switch X is energized, this switch closes its contact, its closing being retarded by the action of the inductance 188 in series with its coil.

30 The closing of the contact of switch X completes the circuit for coil 196 of switch Y as follows; from the minus supply line, through switch J, by wire 12, by wire 192, by wire 193, through contact 194 of switch X, by wire 195, through coil 196 of switch Y, by wire 197, by wire 52, by wire 23, by wire 24, through switch J to the plus line. Switch Y will operate and open its two contacts, 49 and 198. The opening of contact 45 198 removes a short circuit around a part of resistance FS which is in parallel with the series field GSF of the generator GE. The series field GSF is connected in the circuit between the armature of the generator 50 GE and the armature of the hoisting motor M, and resistance FS is placed in shunt with this field. When the switch Y is not energized, part of this resistance FS is short circuited by contact 198 of switch Y, the 55 circuit being by wires 199 and 200. The amount of this resistance that is short circuited may be varied to obtain the desired strength of the generator series field. This field is so wound that without any resistance 60 in parallel with it, it would have too great an effect for the proper operation of the car. The desired strength of this field is obtained by using a low resistance shunt. By increasing the amount of this shunting resistance 65 when the switch Y operates, the strength of

the series field is increased for the leveling operation. The opening of the other contact 49 of switch Y opens the parallel circuit around the brake magnet through resistances PBR¹ and PBR².

70 When the circuits are closed as just traced the elevator car is running in the up direction on the high speed of the leveling operation. As the car gets nearer to the third floor landing, roller 87 on arm 86 of leveling switch L runs off the surface 163 onto inclined surface 201 of the cam 2. This results in the opening of contact 171 of the leveling switch, thereby opening the circuits for the high speed of the leveling operation. The opening of this contact inserts resistance XFR in series with resistance GFR and the generator shunt field GF, causing this field to be weakened. A lower voltage is supplied by the generator GE to the hoisting motor M 85 and the latter drives the car at a reduced speed, which is the low speed of the leveling operation. A condenser C¹ is placed in parallel with the contact 171 of the leveling switch to eliminate arcing when this contact 90 opens.

95 As the car continues toward the landing, roller 87 remains in contact with surface 201 of cam 2 and shortly before the car is level with the landing the roller 87 rolls off of surface 201 onto surface 202 of cam 2 thereby opening contact 169 of leveling switch L. The opening of this contact breaks the circuit to the coil 19 of reversing switch B, the coil 166 of switch P and the coil 21 of switch H, thereby deenergizing these switches which open and disconnect the generator field GF and the brake magnet coil 40 from the line.

100 The holding coils 105 of switch B and 111 of switch H have already been deenergized when contact 171 of leveling switch L opens, so that these coils have no effect at that time. The circuit to these coils was opened by contact 108 on switch D and the contact 145 on switch N, the latter switch having opened as the current was reduced in the generator shunt field GF.

105 Upon deenergization of coil 166 of switch P, its contact 175 opens. This results in the opening of the circuit through the coil 173 of switch R, so that it opens its upper contacts and closes its bottom contact. The opening of contact 190 of switch R deenergizes coil 187 of switch X which thereupon 110 opens its contact 194, its opening, however, being delayed by the action of inductance 188 in series and resistance PR² in parallel with the coil 187. The opening of contact 194 of switch X deenergizes coil 196 of switch Y 115 so that it closes its contacts 198 and 49. The opening of contact 185 of switch R opens the circuit to coil 181 of switch V which thereupon closes its contact 122. The closing of contact 122 of switch V, and contact 120

71 of switch R short circuits resistance XFR and the portion of resistance GFR between points 205 and 79. The opening of contact 177 of switch R opens the connection between the up and down feed fingers, 6 and 180, of car switch A. The closing of contact 198 of switch Y short circuits part of resistance FS in shunt with the generator series field GSF, thereby decreasing the strength of this field. Contact 49 of switch Y establishes the parallel circuits around the brake magnet coil through the resistances PBR¹ and PBR², after giving a quick application of the brake for bringing the car to a stop at a floor when under the control of the leveling switch, the resistance PBR alone being in parallel with the coil of brake BR during the delayed closing of contact 49. The switches are now in position for the next operation and the elevator car is level with the third floor landing, the accuracy of the stop being determined by the positioning of the cams with reference to the landing and the controlling system described.

25 The above description of the operation of the elevator is for an up motion of the car by both the car switch and the leveling switch. A similar operation is obtained for an operation of the car in the down direction, 30 the operator in the car moving the car switch in a direction opposite to that described above. When leveling in the down direction, the other set of contacts are closed as a result of roller 89 on arm 88 being against cam 3.

The self leveling operation as described above may be summarized as follows: On approaching the landing, the operator in the car brings the car switch handle to the center position at such a time as to bring the car to a low speed within the leveling zone, say for instance, in the high speed zone below the landing. This action drops the auxiliary leveling switch T, the contact of which interrupts the current for the leveling switch motor and allows the leveling switch rollers to come into contact with the cam. As it is assumed that the car is in the high speed zone, both high and low speed contacts for the up direction in the leveling switch close. Switch P operates, completing circuit for switch R, which makes circuits for switches V, X, and Y as described above. When the low speed point on the cam is reached, the high speed contact on the leveling switch is opened, thereby inserting resistance XFR in series with the generator shunt field GF and the resulting decreased voltage of the generator gives a very slow speed to the elevator car. On reaching the end of the cam, the low speed leveling switch contact opens, dropping the reversing switch and applying the brake.

Should the car overtravel the landing so that the down low speed leveling switch

contact is made by the cam 3, current is supplied to the direction switch C and switch P. Switch P makes circuit for switches R, V, X, and Y as before set forth. As the high speed contacts on the leveling switch are open at the time, resistance XFR would be in series with the generator field GF, resulting in a very weak generator field, if switch V operated immediately to open its contact 122. Therefore the operation of switch V is retarded so as to leave the resistance XFR short circuited for a short time in order to momentarily provide sufficient voltage for the motor armature to insure the starting of the car upon the leveling switch being closed when the car is in the slow speed zone. The operation of switch Y in opening its contact 198 increases the resistance of the shunt FS across the generator series field, GSF, thereby causing a greater proportion of the armature current to pass through the series field winding. The action of the series field is to regulate the voltage on the hoisting motor armature so as to compensate for variations of load in the elevator car. Switch Y is retarded in opening its contacts by the retarded action of switch X in order to prevent the immediate change in the proportion of armature current flowing through the series field upon the closing of the leveling switch slow speed contacts.

Assuming that the elevator car is traveling in an up direction to a landing, on the leveling switch, and it is desired to operate it downwardly. The coil of switch B is energized and since the leveling switch controls the operation of the direction switches B and C, and the bottom contact 74 on switch B has cut off the direct feed from the minus supply to the coil of the direction switch C, it would be necessary to wait until the up leveling operation had been completed except for the fact that contact 177 of switch R which is closed during the leveling operation completes a circuit supplying a feed from the minus supply to both fingers 6 and 180 of the car switch A. Movement of the handle 4 of the car switch to the down direction first completes a circuit through the down direction switch C and switch H in a similar manner to that set forth for the direction switch B, but due to the fact that direction switch B is energized, the walking beam 54 between these switches prevents switch C from operating. Further movement of handle 4 in the same direction to cause the segment 5 to bridge three fingers 180, 206 and 207, on the down side closes the circuit of the coil of switch T which operates to energize the motor LM for raising the arm 85 of leveling switch L. This results in the switch arms 86 and 88 with their rollers being moved so as to be out of line of the cams 2 and 3 and thus

opens the contacts of the leveling switch. The up direction switch B is thereby deenergized and when it opens, switch C, which has already been energized, will close. Further movement of handle 4 will energize the switches D, E, F, G, N, O, Q and Z so as to operate them in the manner set forth in connection with the operation of the elevator car in the up direction. While the 10 elevator car is traveling downward at full speed the remaining switches, B, P, R, V, X and Y, are deenergized.

The control for the elevator affords a smooth operation from one speed to another 15 and in stopping. While in the arrangement disclosed the operation of the car leveling switch L by motor LM and switch T is controlled from the third finger of the car switch A, it is found desirable in some instances to interchange the order of these 20 fingers and allow it to operate as fourth or fifth in order. In this case either one or two accelerating switches, D, or D and E, may be controlled from the car switch A 25 without shifting the leveling switch L to inoperative position. As a result a continuous operation may be had in bringing the elevator cars of various rated speeds to a stop at the landings.

30 In order to obtain a smooth operation while stopping or reversing the car, the brake BR is controlled for quick, medium and slow application. The coil 40 of brake BR has a parallel resistance PBR across it 35 which is never opened. This prevents an excessive voltage across the coil when the circuit to it is broken, and the stop at the landing controlled by this parallel resistance is a quick application of the brake to 40 keep the car from sliding past the landing. This operation takes place when stopping by operation of the leveling switch, in which case the contact 49 of switch Y is maintained open until the car has stopped, the 45 action of this switch, Y, being delayed by the retardation of switch X. For stops between landings, the application of the brake is determined by parallel resistance equivalent to resistances PBR, PBR¹, and PBR² 50 all in parallel for a slow brake application, which brings the car to rest gradually and without shock. In this case switch Y remains inoperative in the stopping operation and its contacts remain closed, and switch 55 H opens, closing its contact 46 so that all three resistances are in the circuit. When making a quick reversal resistances PBR and PBR² are in parallel around the brake coil so as to give a medium application of the brake, just slow enough so that the brake will not set when making the reversal. Here switch Y remains inoperative and contact 60 46 of switch H does not close. It will be understood that resistances PBR, PBR¹ and 65 PBR² are so chosen as to give a discharge

path of the proper resistance for the brake coil for each condition.

What is claimed is:—

1. In an electric elevator system, the combination with a hoisting motor and a variable voltage source of energy therefor, of means responsive to the speed of said motor for jointly controlling the field regulation of said motor and energy input into the motor from said source to decrease the speed of the motor in the event that the motor speed rises to a predetermined value and to increase the speed of the motor after it falls to a predetermined value. 70 75

2. In an electric elevator system, the combination with a hoisting motor, of control means therefor comprising a resistance adapted to be inserted in series with the motor field winding, and a variable voltage source of power supply for the motor, and means responsive to the speed of said motor for short circuiting said resistance and decreasing the voltage of said power supply in the event that the motor speed rises to a predetermined value and to increase the speed of the motor after it falls to a predetermined value. 80 85 90

3. In an electric elevator system, the combination with a hoisting motor, of control means therefor comprising a resistance adapted to be inserted in series with the motor field when the motor has reached a certain speed, a variable voltage source of power supply for the motor having electromagnetically operated switches adapted to 95 control the voltage supplied, means in the control system for the hoisting motor for operating said switches for increasing the voltage to the maximum and for inserting said resistance in series with the motor field, 100 and means operable to short circuit said resistance and operate one of said switches to 105 lower the voltage of the power supply in the event of over speed of the motor.

4. In combination, an electric motor, a variable voltage generator for supplying energy to said motor, said generator having a field winding, means for impressing voltage of certain values on said winding to cause the motor to run at normal speeds, and means for impressing voltage of a lower value on said winding to cause the motor to run at a lower speed than normal speeds, said last named means comprising means for initially and momentarily impressing voltage of a higher value than said lower value on said winding. 110 115 120

5. In combination, an electric motor, a variable voltage generator for supplying current to said motor, said generator having a field winding, a source of current for said winding, means for controlling the direction of the flow of current from said source to said winding to control the direction of rotation of said motor, means for causing the 125 130

application of voltage of certain values from said source to said winding to cause the motor to run at normal speeds in each direction of rotation, and means for causing the 5 application of voltage of a lower value than said certain value from said source to said winding to cause the motor to run at a lower speed than normal speeds in each direction of rotation, said last named means comprising means for initially and momentarily causing the application of voltage of a higher value than said lower value from said source to said winding.

6. An electric elevator system comprising 15 in combination, an elevator car, a hoisting motor, a variable voltage generator for supplying energy to said motor, control means including a leveling switch operable by movement of the car in conjunction with 20 cams in the elevator hatchway for causing the application of voltage of two different values to the generator field winding to cause the motor to operate the car at a fast and a slow leveling speed, and means for 25 initially and momentarily causing the application of voltage to said winding of a higher value than that caused to be applied to obtain said slow leveling speed in the event that the leveling switch takes the control 30 for slow leveling speed.

7. In an electric elevator system, the combination of a hoisting motor, a variable voltage generator for supplying power to said motor and having a reversible field, a control 35 means therefor including direction switches and accelerating switches for operating the motor at normal variable speeds in either direction with the power supplied by said generator, and control means for 40 operating said motor at lower than the normal speeds in either direction by energy supplied from said generator at lower voltages, said last named means comprising means for initially and momentarily causing 45 the application of voltage of a certain value to said winding and thereafter causing the application of voltage of a lower value than said certain value to said winding.

8. In an elevator system, an elevator car, 50 a hoisting motor therefor, a variable voltage generator for supplying current to said motor, said generator having a field winding, a source of current for said field winding, means including reversing switches for controlling 55 the direction of the flow of current from said source to said winding to control the direction in which the motor operates the car, means including accelerating switches for causing the application of voltage of certain values from said source to said 60 winding to vary, within certain limits, the voltage applied from said generator to said motor to cause the motor to run at normal variable speeds in each direction of rotation, 65 and means, including a leveling switch car-

ried by said car and cams in the hatchway for operating said leveling switch, for causing the application of voltage of a lower value than said certain values from said source to said winding to cause the voltage applied from said generator to said motor to be below said certain limits and thus cause the motor to run at a lower speed than normal variable speeds in each direction of rotation to facilitate the leveling of the car 70 at the landings, said last named means comprising means for initially and momentarily causing the application of voltage of a higher value than said lower value from said source to said winding. 75

9. In an electric elevator system, the combination of an elevator car, a hoisting motor, a generator having a separately excited field winding and a series field winding and adapted to supply power to the hoisting motor at a variable voltage, means for controlling the supply of power to the motor, a leveling switch actuated by movement of the elevator car for controlling said power supply to the motor, and means controlled by 80 the leveling switch for causing a change of the ampere turns of the series field for a given armature current during the operation of the motor by said leveling switch. 85

10. In an electric elevator system, the combination of a motor, a hoisting drum and an electrically operated brake, a source of energy for supplying power to the motor and for operating said brake, a control system including means for operating the motor 100 in either direction from the source of power, means for reversing its direction and bringing it to a stop, means for releasing the brake, and means for regulating the speed with which the brake applies to obtain a 105 slow application of the brake for stopping the elevator car between landings, a medium application thereof on the reversal of the operation of the hoisting motor, and a quick application thereof when stopping at landing levels. 110

11. In an electric elevator system, the combination of a hoisting motor, a variable voltage generator for supplying power to said motor, a control system including direction switches, a plurality of accelerating switches interlocked with said direction switches and with each other for controlling the voltage applied to the motor from the generator, means for retarding the operation of the accelerating switches in opening when bringing the motor to a stop, and means operated after the motor has attained a predetermined speed operable to retard the opening of the direction switches. 115 120

12. In an electric elevator system, the combination of a hoisting motor, a variable voltage generator for supplying power to said motor, a control system including direction switches, a plurality of accelerating 125

- switches interlocked with said direction switches and with each other for controlling the voltage applied to the motor from the generator, a car switch on the elevator car
- 5 having a plurality of contacts for controlling the direction switches and interlocked accelerating switches, means for retarding the opening of said switches, and a switch operated after the motor has attained a pre-
- 10 determined speed and having a retarded action in opening adapted to delay the opening of the direction switches when the motor speed is decreasing.
13. In an electric elevator system, the combination of a hoisting motor, a variable voltage generator for supplying power to said motor, a control system including direction switches, a plurality of accelerating switches interlocked with said direction
- 15 switches and with each other for controlling the voltage applied to the motor from the generator, a car switch on the elevator car for controlling said switches, a leveling switch adapted to be actuated by cams in the
- 20 elevator hatchway for operating the elevator car, means controlled by said car switch for displacing said leveling switch to an inoperative position, and means for retarding the
- 25 operation of the said direction and inter-
- locked accelerating switches in opening, and means for returning the leveling switch to its operative position before the direction switches open.
14. In an electric elevator system, the combination of a hoisting motor, a variable voltage generator for supplying power to said motor, a control system including direction switches, a plurality of accelerating switches interlocked with said direction
- 30 switches and with each other for controlling the voltage applied to the motor from the generator, a car switch on the elevator car for controlling said switches, a leveling switch adapted to be operated by cams in the
- 35 elevator hatchway and adapted to energize said direction switches for operating the elevator car at low speeds and bringing it to the landing level, and means for rendering the car switch operative to take the control of said direction switches for operating the elevator car in either direction at any time during the operation of the car by
- 40 said leveling switch.
- 45 In testimony whereof, we have signed our names to this specification.

RAYMOND A. WAITE.
GEORGE W. LAUTRUP.
